UNITED STATES PATENT OFFICE.

EZRA T. GILLILAND, OF BOSTON, MASSACHUSETTS, ASSIGNOR TO THE AMERICAN BELL TELEPHONE COMPANY, OF SAME PLACE.

SUSPENSION OF AERIAL CABLES.

SPECIFICATION forming part of Letters Patent No. 310,938, dated January 20, 1885.

Application filed July 2, 1884. (No model.)

To all whom it may concern:

Be it known that I, EZRA T. GILLILAND, of Boston, in the county of Suffolk and State of Massachusetts, have invented certain Improvements in Suspension of Aerial Cables, of which the following is a specification.

The object of my invention is to provide an improved support or suspension for aerial cables.

My invention consists in providing two or more supporting-wires, or one supporting-wire and a leading-in wire, and a cable-clip, formed preferably of sheet metal, the opposite sides or edges of which are formed into hooks, 15 stirrups, or passages of appropriate dimensions—one for the reception of the supported cable or cables, and the other with two or more separate hooks or passages for the reception of two or more separate supporting-wires, or one supporting-wire and a leading-in wire.

Heretofore a cable has been suspended by a single supporting-wire, and cable-clips have been used having but one receptacle for the 25 supporting-wire and one for the supported cable, and when the supporting-wire became weakened by corrosion or wear the entire suspension was lowered to the ground for the purpose of replacing the supporting-wire.

In my invention, by the use of two suspending-wires, or one suspending-wire and a leading-in wire, it is possible to replace any portion without lowering or disturbing the whole suspension.

I also provide a device for attachment to the end of the suspension-wire or to the leading-in wire, whereby the wire or cable to be placed in position may be smoothly drawn through the hooks or passages in the clips. It 35 consists of a metal barrel, screw-threaded on one end to receive one wire, and an opening in which to form a swivel-joint with the other wire, one or both ends of said barrel being tapered off to a smaller diameter than that of the passage in the cable-clips.

I have found it desirable in some cases to provide for hanging additional cables onto the same suspending-wire. This is done by slightly varying the form of my improved cable-clips. Two cables may also be suspended

from two suspending-wires by the use of my improved cable-clip, which is adjustable for this purpose, whereby a more rigid suspension is obtained, at the same time providing for the replacement or substitution of any part 55 of the suspension.

Figure 1 shows a section of a suspended cable employing my improved clip, a suspending-wire, and a leading-in wire. Fig. 2 shows one form of my improved clip. Fig. 3 shows a 60 complete suspension, embracing Figs. 1 and 2. Fig. 4 is the device for leading a wire through the clips. Fig. 5 shows the leading-in device in operation. Fig. 6 shows a combination suspension. Fig. 7 is a modification. 65

In Fig. 1, M is an aerial cable suspended by the clip C from a wire, s, of sufficient tensile strength. The clip C is shown enlarged in Fig. 2, and consists of two sections, b d and a e, cut preferably from a brass sheet, the opposite sides formed with hooks or stirrups c and d, a and e, according to the intended use. The two portions are brazed, soldered, or riveted together. If one cable only is to be provided for, the hooks to receive the cable are 75 bent into position, having their central section in substantially the same vertical plane; if to receive two cables, they diverge as in Fig. 6. A clip is thus formed having four or more stirrups. Through one stirrup is passed the 80 suspension-wire, as in Fig. 1, and through its companion a leading-in wire, preferably of some incorrosive metal, as w. If at any time the suspension-wire becomes weakened and it is necessary to replace it, I employ such a 85 device as shown at N in Fig. 4. A suitable metal cylinder, N, is provided, tapered off at one or both ends. At one tapered end, t, a passage is made about the size of the leading-in wire, and meeting this from the opposite 90 end is a passage about the size of the suspension-wire, in which is cut a screw-thread, x, to take a screw cut upon the end of the suspension-wire. The leading-in wire is introduced, its ends knotted to form a swivel-joint, 95 y, the suspension-wire screwed into the opposite end and drawn through the clips, as shown in Fig. 5. When the new wire has been placed in position, the leading-in wire is attached to the old suspension-wire and drawn 100

into position as the old wire is drawn out, where it remains until again required for service. A desirable modification of this arrangement is shown in Fig. 6, where, in place of a leading-in wire, I use a second suspension-wire, s' , and carry a second cable, M' , all in the same clips. If one suspension-wire becomes worn, it may be replaced by employing it as a leading-in wire, the entire weight of the suspension during the process of substitution being transferred to the other suspension-wire.

The cable-clip above described is adjustable, and may be so manipulated as to be readily adapted to support two cables from one wire, as shown at $M M'$ in Fig. 7, or one cable and two wires, as in Fig. 1.

The cable-clip above described being formed of sheet metal of sufficient width to prevent its turning, biting into, and holding a wire which is being drawn through it, the replacement of one of the supporting-wires is rendered possible. Moreover, the two eyes or loops for the supporting-wires at the top of the vertical stem are in close proximity, and practically in the same vertical line with the stirrup or stirrups; hence, if it becomes necessary to replace one of the members of the suspension, the other two members hold the clip in the normal position while the substitution is being effected. If the loops for the supporting-wires are too far apart, or not sufficiently elongated to prevent turning, it would be difficult, if not impossible, to replace one of the wires in the manner pointed out.

What I claim, and desire to secure by Letters Patent, is—

1. A suspension for aerial cables, comprising two or more wires and a series of cable-clips, each clip having a vertical stem, two eyes or loops at the top of said stem, and a stirrup or stirrups at the lower end, substantially as described.

2. A suspension for aerial cables, consisting

of a suspending-wire, a leading-in wire, and a series of cable-clips, hooks, or connections.

3. A suspension for aerial cables, consisting of a suspending-wire of considerable tensile strength, a leading-in wire formed of a metal which may be of low tensile strength, but which is less liable to corrode, and a series of cable-clips, hooks, or connections.

4. An aerial suspension consisting of a suspending wire or wires, two or more cables, and a series of clips or connections, each clip having a separate hook or stirrup for each cable, so that each cable is supported independently of the others, substantially as described.

5. A cable-clip of sheet metal, having a stem vertical when in position, and elongated loops or passages for the reception of three or more wires or conductors, substantially as described.

6. A cable-clip formed of two pieces of sheet metal fastened together and provided with hooks or passages for the reception of three or more wires, cables, or conductors, substantially as described.

7. In a device for drawing cables through suspension devices, swivel-jointed connection having a tapering end for connection thereat with a leading-in wire, and screw-threaded at the opposite end to receive the threaded end of the wire to be led in, substantially as described.

8. The improved cable-clip described, being of flexible metal and having a stirrup or stirrups for the cables, and two elongated loops or eyes in close proximity for the supporting-wires, as set forth.

In testimony whereof I have signed my name to this specification, in the presence of two subscribing witnesses, this 24th day of June, 1884.

EZRA T. GILLILAND.
